ELECTRON DISCHARGE DEVICE OF THE
CAVITY RESONATOR TYPE WITH
FEEDBACK

John J. Livingood and Winfield W. Salisbury,
Cedar Rapids, Iowa, and Edward S. Welch,
Cambridge, Mass., assignors to the United
States of America as represented by the Sec-
retary of War

Application February 18, 1946, Serial No. 648,542.

4 Claims. (Cl. 315—6)

1

This invention relates to an electronic device, and, more particularly, to vacuum tubes of the resnatron type.

It is at present known to obtain the necessary feedback in an oscillating resnatron by the provision of one or more cathode supported conductors, wires or rods that extend radially outwardly from the cathode structure of the tube through the control and the screen grids toward the anode structure, with the outer extremities of the rods or wires in spaced relation to the anode. Such wires couple the cathode-control grid cavity and the screen grid-anode cavity of the resnatron. Heretofore, the wires would have been of molybdenum, preferably soldered into a threaded piece of copper rod screwed into a tapped drilling in the cathode structure, adjacent one end of the filament thereof. This practice has been found to possess a number of disadvantages. The proper length of feedback wire is found by experimentation. The feedback capacity between the wire and the anode cannot be altered or varied without at least partially dismantling the resnatron, and changing the length of the wire or wires. The optimum length of the wire is not quite the same for the different frequency adjustments of the resnatron, because the position of the feedback capacitors shifts with respect to the standing waves of voltage along the resnatron as the wavelength is altered. The arrangement is poor, also, from a maintenance standpoint because, to change the cathode, the cathode, control grid and screen grid must be withdrawn from the tube structure so that the feedback wire or wires may be removed before the cathode can be withdrawn from within the control grid; and because, occasionally, the threaded copper pieces melt under the high temperature present within the tube, and become welded into the drillings in the cathode structure. Should the latter be the case, it becomes necessary, then, to break off one or more of the molybdenum wires before the cathode can be completely isolated from the grids.

An object of this invention is to improve the structure of a resnatron to obviate and to minimize the referred-to difficulties, and to provide the desired feedback in a resnatron in a novel and more advantageous manner.

A feature of this invention comprises the provision of variable or adjustable feedback means in a resnatron.

Another feature comprises the provision in a resnatron of capacitive feedback means supported from or on the anode of the device.

Still another feature comprises incorporating

2

feedback means in a resnatron in the form of one or more conductors, wires or rods supported outside of the cathode structure but extending inwardly toward the cathode structure.

5 A further feature comprises feedback means within the resnatron; adjustable externally of the resnatron for varying the feedback, without dismantling the resnatron, or after the resnatron has been assembled, or during operation of the resnatron.

An additional feature comprises the addition of a suitable shield or other protective means on the cathode structure to guard against high potential arc-overs when inwardly extending feedback conductors, wires or rods are incorporated in the resnatron structure.

Still other objects and features of the invention, together with their attendant advantageous aspects, will be obvious from the general and the 20 specific descriptions which follow hereinafter.

In accordance with the invention, capacitive feedback between the cathode-control grid cavity and the screen grid-anode cavity of a resnatron is incorporated in a tube of that type by the provision of one or more conductors, rods or wires 25 supported from or electrically connected with the anode, that extend radially inwardly from the outer wall of the resnatron through the screen grid and the control grid of the device, toward the cathode structure, the wire or wires being at its or their inner ends in spaced relation to the cathode structure. The wire or wires are preferably of good electrical and thermo-conducting material, for example, solid copper rod, each

30 mounted at the inner end of water or other fluid-cooling tubing that extends from the outside of the resnatron through suitable vacuum sealing joints or means in the wall of the resnatron along radial lines. The tubing and, therefore, its associated wire may be adjusted slidably to and from the cathode structure from outside of the resnatron. To protect the cathode structure, and particularly thin walled members, such as a Sylphon, that may be associated with the cathode structure, against high potential arc-overs from the feedback rod or rods during testing or the 35 operation of the device, a suitably proportioned small sheet or disk of metal, for example, copper, may be mounted on the cathode structure, extending parallel to the cathode structure's axis and to the Sylphon, oppositely disposed with reference to and spaced from the innermost end of the feedback rod, the rod and the disk together forming an adjustable capacitor. If two

40 45 50 55 or more of these adjustable feedback rods are

utilized, they may be spaced at equidistant positions along radial paths in the resnatron. To permit a maximum cooling of the feedback rod or wire, it may be preferred to shorten the wire or rod to the utmost so that, in such an arrangement, the movable element of the adjustable capacitor might constitute a thin plate or stub at the inner end of the tubing. Obviously, with the arrangement just described, the amount of capacitive feedback may be adjusted from outside 10 the resnatron, eliminating the necessity to dismantle the device, permitting ready experimentation to ascertain the appropriate spacing of the feedback rod from the cathode structure in order to provide the needed or the desired change in 15 capacity, and eliminating the other referred-to difficulties present when the feedback rods are supported from the cathode structure.

A more complete understanding of the invention will be derived, it is believed, from the detailed description that follows, read with reference to the appended drawing, wherein:

Fig. 1 is a cross-sectional view of a portion of a resnatron illustrating the manner in which the invention may be embodied in such a device;

Fig. 2 is a plan view of the device of Fig. 1, taken along the line 2—2 thereof; and

Fig. 3 is an enlarged cross-sectional view of a portion of the device of Fig. 1, taken along the line 3—3 thereof, in order to show in detail the construction and relationship of the parts of the adjustable feedback means for a resnatron in accordance with this invention.

With reference to the drawings, there is shown so much of the structure of a resnatron as necessary for an understanding of this invention. The resnatron's outer walls comprise substantially cylindrical metallic sections 12, 14 secured firmly together by a plurality of fastening devices 16 and clamping therebetween, the anode structure 18 of the resnatron, and a feedback rod supporting member or annulus 20 which may be, for example, of brass. The adjacent surfaces of the sections 12, 14, the anode 18, and the member 20 are vacuum sealed by means of sealing gaskets 22 which may be, for example, of rubber, and maintained in electrical contact by electrically conductive gaskets 24, which may be, for example, of tin. The electrode structure of the resnatron in accordance with known practice may comprise a cathode-control grid cavity 26 including cathode structure 28 and control grid 30 and a screen grid-anode cavity 32 including the anode structure and the screen grid 34. The cathode structure may include a Sylphon 36 and a plurality of filaments 38, and the control grid may contain a plurality of slots or apertures 40, each of which is located opposite a cathode filament to provide passage for electrons emitted from the cathode filaments. One or more openings 42 may be provided in the control grid for the passage through the control grid of one or more feedback conductors as will be described more fully further on.

The screen grid 34 may comprise a plurality of lengths of metallic tubing, for example, of copper, thereby permitting water, or other fluid, cooling of the screen grid. Variable capacitive feedback is provided by a fixed or stationary disk, sheet or plate 44, secured to the cathode structure adjacent one end of the cathode filaments, and a radially adjustable, conductor, wire, or rod 46, three sets of which are shown spaced at approximately 120°. The disk protects or

guards the thin-walled Sylphon against being punctured, and thereby letting fluid, for example, water, from the Sylphon into the highly evacuated cavities, by possible high potential arcovers from the rod 46 during the operation of the resnatron. The enlarged cross-sectional view of Fig. 3 shows the adjustable variable feed-back means in greater detail.

It comprises the rod 46 mounted on and closing one end of the outer tube 48 of a pair of coaxial tubes 48, 50, which may be of copper tubing, adapted to be coupled at their open and outer ends 52, 54 to a source (not shown) of cooling fluid, for example, water. The coaxial tubes 48, 50 are slideable as a unit to and fro within a central aperture 56 in a guide and stop plate 58, a central aperture 60 of a vacuum seal or joint 62, and the multi-spring fingered end 64 of a metallic tube 66. The tube 66 threads into a radial tapped drilling 68 in member 20. The seal 62 may comprise the double flanged disk 70, the flange 72 making a soldered joint with the member 20, and the flange 74 being engaged by the L-sectioned clamp 76 that secures the sealing gasket 78, which may be of rubber, in place. The plate 58 is supported from the disk 70 by suitable spacers 80 and fastening devices 82, and limits the maximum inward movement of the feedback rod. In a specific embodiment constructed in accordance with the invention, the rod 46 was of the order of one-eighth inch diameter; the tubes 48, 50 of the order of five-sixteenths inch and one-eighth inch diameter, respectively; and tube 66, of the order of one-half inch diameter. If it should be necessary to cut away one or more tubes comprising the screen grid to permit passage of the feedback rod, obviously connecting pieces of screen grid tubing may be employed to provide continuous paths through the screen grid tubing for flow of cooling fluid therein. The opening in the screen grid for the feedback rod should be made of sufficient size to reduce the direct capacity from the anode to the screen grid that the feedback rod or rods provide.

The cathode-grid cavity of an oscillating resnatron must be excited by a fraction of the output voltage generated in the screen-anode cavity. When capacitive feedback is used, the feedback capacitor and the impedance of the cathode-grid circuit are connected in series across the output voltage in order to form a potential divider such that voltage of the proper magnitude and phase is impressed across the cathode-grid circuit. In this invention, the capacitance exists between the cathode structure and the rod which is connected to or supported on the anode; thus the cathode-grid and the anode-screen cavities are connected as required.

Although the invention has been described with reference to a specific structural embodiment, it is obviously not limited thereto and the illustrative structures, proportions, and materials may be varied without departing from the spirit of the invention, the scope of which is evidenced by the prior art and appended claims.

What is claimed is:

1. An electron discharge device of the resnatron type comprising cylindrical cathode, control grid, screen grid, and anode electrodes mounted concentrically in the order mentioned with said anode electrode surrounding the other electrodes, an input cavity resonator coupled between said cathode and control grid electrodes, 70 an output cavity resonator coupled between said

anode and screen grid electrodes, a conductive feedback probe extending radially into said input resonator, said probe being capacitively coupled to said input resonator, means for adjusting the position of said feedback probe during operation of said discharge device, said adjusting means including means mounting and sealing said feedback probe through said anode electrode and electrically connecting said feedback probe and said anode electrode, and means located outside said anode electrode for moving said feedback probe with respect to said anode electrode.

2. An electron discharge device of the resonatron type comprising cylindrical, cathode, control grid, screen grid, and anode electrodes mounted concentrically in the order mentioned with said anode electrode surrounding the other electrodes, an input cavity resonator coupled between said cathode and control grid electrodes, an output cavity resonator coupled between said anode and screen grid electrodes, a conductive feedback probe extending radially into said input resonator, said probe being capacitively coupled to said input resonator, and means for adjusting the position of said feedback probe during operation of said discharge device, said adjusting means including electrically conductive gaskets mounting and sealing said feedback probe through said anode electrode and electrically connecting said feedback probe and said anode electrode, and means located outside said anode electrode for moving said feedback probe with respect to said anode electrode over said gaskets.

3. An electron discharge device of the resonatron type comprising cylindrical cathode, control grid, screen grid, and anode electrodes mounted concentrically in the order mentioned with said anode electrode surrounding the other electrodes, an input cavity resonator coupled between said cathode and control grid electrodes, an output cavity resonator coupled between said anode and screen grid electrodes, a conductive feedback probe electrically and mechanically connected to said anode electrode and extending radi-

ally into said input resonator, said probe being capacitively coupled to said input resonator, and a conductive element mounted on said cathode electrode and positioned between said cathode electrode and said feedback probe for shielding said cathode from sparks from said feedback probe and providing capacitive coupling between said feedback probe and said cathode electrode.

4. An electron discharge device of the resonatron type comprising cylindrical cathode, control grid, screen grid, and anode electrodes mounted concentrically in the order mentioned with said anode electrode surrounding the other electrodes, an input cavity resonator coupled between said cathode and control grid electrodes, an output cavity resonator coupled between said anode and screen grid electrodes, a conductive feedback probe electrically and mechanically connected to said anode electrode and extending radially into said input resonator, said probe being capacitively coupled to said input resonator, the innermost end of said feedback probe being solid and the rest of said probe being hollow and constructed so as to facilitate circulation of a fluid therethrough, and fluid circulating means coupled to the outer end of said probe.
